1

The present invention relates generally to devices for initiating the arc in electronic gaseous conduction devices, and particularly in gaseous conduction device of the types which have control electrodes, and which rely for their operation upon electrical conductivity of gas or ionized vapor. Accordingly, the present invention finds particular application to sealed tubes containing mercury vapor and varified gas, such as helium, xenon, and the like, in which initiation of the arc is caused during each period of an alternating current by means of a priming electrode. One tube of this character, which is generally known in the art, is commonly designated by the name "ignitron."

In order to accomplish initiation of an arc in devices of the ignitron type, it is necessary to release in the ignitor electrode of the ignitron, which corresponds with a control electrode, a fairly intense current, having a magnitude of about 5 amperes, at a fairly high voltage, say about 30 volts. The duration of the current which is applied to the ignitor electrodes may be relatively short, of the order of one-ten thousandths of a second or less. It is possible to obtain a flow of current of the character described by discharging a fairly high capacity, which is charged to a voltage of 100 volts, through a relatively low resistance.

For many applications of control electrode controlled gaseous conduction devices, and particularly for the controlled rectification of alternating current, for voltage and current regulation systems in general, and for frequency transformation systems, it is essential that the timing of the application of current to the timing of firing electrode be precisely defined, because the operation of such systems depends fundamentally on the relative phase of the firing voltage applied to the control electrode and the alternating voltage applied between the anode and cathode of the gaseous conduction device.

One presently accepted and normal technique for controlling firing of gaseous conduction devices consists of the employment of auxiliary ionic tubes for this purpose. For example, for the firing of ignitrons, it has become conventional to employ a thyratron connected in series with the ignitor electrode, maintaining the control electrode of the thyratron normally below

2

firing voltage, and bringing the control voltage applied to the control electrode of the thyratron up to a firing value at the instant when firing of the ignitron is desired. When the ignitron fires, the thyratron permits a fairly high current to pass to the ignitor electrode, this current being limited only by such resistance as may be connected in series with the ignitor electrode. This current is sufficient to fire the ignitron, but once 10 the ignitron has fired the total current flow therethrough is not subject to control. Accordingly, in order to control the average value of the ignitron current, it is conventional to feed the control electrode of the thyratron with pulses 15 of voltage, which are de-phased in relationship to the alternating voltage applied to the anode of the thyratron, thereby controlling the firing times of the ignitron. It is conventional to obtain a controlled de-phasing of the grid voltage 20 of the thyratron by means of a saturable reactor and associated resistances, by means of phase controllable transformers, and by similar systems. While the conventional procedures have proven 25 satisfactory, in general, they present the disadvantage of being inherently extremely complicated and expensive, since it is necessary to provide a large number of control components which are heavy, delicate, fragile, and expensive in first cost, and which are subject to considerable 30 maintenance difficulties.

The present invention remedies the defect by furnishing means for firing gaseous conduction devices, and particularly ignitrons, by means of extremely simple, sturdy and cheap control devices, which are easy to maintain and to regulate.

It is, accordingly, a broad object of the invention to provide novel firing devices for gaseous conduction electronic tubes.

It is, accordingly, a broad object of the invention to provide novel firing devices for gaseous conduction electronic tubes.

It is a further broad object of the invention to provide firing systems for gaseous conduction devices generally, which shall be simpler, more economical, sturdier, and easier to maintain and regulate, than has been the case in the prior art.

It is still another object of the invention to provide novel firing systems for an ignitron, which rely upon spark discharges in air.

It is another object of the invention to pro-

vide a system for firing ignitrons by means of controlled spark discharges in air, wherein the spark discharge from a source of relatively low voltage high current is initiated in response to an auxiliary spark discharge produced in response to a relatively high voltage low current source.

It is still a further object of the invention to provide a polyphase system of frequency transformation, which may be employed particularly to reduce the frequency of welding current, while controlling the magnitude thereof.

It is still another object of the invention to provide a system for rectifying alternating current by means of gaseous discharge devices operating in air.

It is still a further object of the invention to provide a system for rectifying alternating current by means of a device which may be controlled by a control electrode, and which operates in air, as an ionic conduction device.

A further object of the invention resides in the provision of a system for frequency division of voltages provided by a polyphase line, by selectively and in predetermined sequence effecting firing of gaseous conduction devices in series with each phase of the line.

The above and still further features, objects and advantages of the present invention will become apparent upon consideration of the following detailed description of various specific embodiments thereof, especially when taken in conjunction with the accompanying drawings wherein:

Figure 1 is a schematic circuit diagram of an ignitron rectifier having an igniting circuit arranged in accordance with the present invention;

Figure 2 is a circuit diagram of a modification of the system of Figure 1;

Figure 3 is a detailed drawing of electrode structure for use in the system of Figure 2;

Figure 4 is a circuit diagram of a modification of the system of Figures 1 and 2, wherein the invention is applied to current rectification or frequency transformation, of voltages supplied by a polyphase line, and wherein control electrode controlled gaseous discharge devices are of the type which operate in air as a gaseous conduction medium;

Figure 4A is a detail view of one of the gaseous discharge devices shown in Fig. 4.

Figure 5 is a schematic circuit diagram of a welding system arranged to transform the frequency of a three phase line to single phase current of lower frequency than that provided by the line;

Figure 6 represents a wave form diagram illustrating the character of current flow in the system of Figure 5;

Figure 7 is a wave form diagram illustrating the character of current flow in the system of Figure 5 when employed for frequency division;

Figure 8 is a further wave form diagram representing current flow in the system of Figure 5, for one mode of operation thereof, and showing the order in which firing of the gaseous conduction devices of Figure 5 are required to take place in order to accomplish the wave form illustrated in the figure; and

Figure 9 is a modification of the wave form diagram of Figure 8 showing the timing pulses and wave form obtainable for a different order of frequency division.

Briefly described, and in accordance with the present invention, I utilize pulses of high volt-

age, but of small current, to effect priming of a spark gap, these pulses of voltage being obtained preferably by means of a circuit maker and breaker operating in conjunction with an induction coil. The sparks generated may then be distributed by means of a distributor of conventional character, which may be driven by means of a synchronous motor, synchronized with line voltage applied to the main gaseous conduction devices. The high priming voltage is utilized to effect ionization in a spark gap. Once ionization has been accomplished a heavy flow of current from a further circuit is caused to pass through the spark gap and to the control electrode of the gaseous conduction device to accomplish firing therein.

Referring now more particularly to the drawings, and having reference initially to Figure 1 thereof, reference numeral 1 identifies an ignitron tube which may be of conventional character per se, and which comprises an anode 2, a cathode 3 and an ignitor electrode 4. The ignitron 1 may be connected in series with an A.-C. line 5, one side of which is connected to the anode 2, and the other side of which is connected to the cathode 3 via a load 6 represented as a resistance.

Firing of the ignitron 1 is accomplished by applying relatively heavy currents to the ignitor electrode 4 at times during the A.-C. cycle of the voltage supplied by the line 5 when the anode 2 is positive. By controlling the firing times within the cycle the average value of the current flowing in the load 6 may be controlled.

Firing current for the ignitor electrode 4 may be generated as follows. A spark gap device is provided having two principal electrodes 7 and 8 and an auxiliary electrode 9, the electrodes being mutually adjacent, and operating in air. The principal electrode 7 may be connected to the ignitor electrode 4 via a protective resistance 10, which serves to limit flow of current to the ignitor electrode 4. The principal electrode 8 may be connected in series with a protective resistance 11, and secondary winding 12 of a transformer 13, to the cathode 3 of ignitron 1. Connected across the secondary winding 12 may be a condenser 14, which becomes charged in response to voltage supplied by the winding 12, and which discharges across the principal electrodes 7 and 8 and through the ignitor electrode 4, when the gas existing in the gap between the principal electrodes 7 and 8 becomes ionized. Normally, the spacing between the principal electrodes 7 and 8 is insufficient to permit break-down or ionization of the gas contained therebetween in response to the voltage developed across the secondary winding 12 of transformer 13. Transformer 13 is energized by means of a primary winding 12' which is connected across the line 5, and is energized therefrom via a phase controlling condenser 15 and resistance 16, which are provided in association with the primary winding 14 in order to advance the phase of the current flowing in primary winding 14 relative to the voltage existing on the line 5.

Ionization of the air existing in the gap between the principal electrodes 7 and 8 is accomplished by applying to auxiliary electrode 9 a transient high voltage, preferably at low current. To this end, voltage is derived from the line 5 via a transformer 17, and is applied to a rectifier arrangement 18, which may be of the well known Rectox type, at the output of which is

provided a filtering arrangement 19. Across the inductance 20 of filter 19 is then developed a D-C. voltage of constant magnitude. Connected across the inductance 20 or across the filter 19, and in series with one another, are a pair of breaker points 21, which are adapted to open and close in response to a rotating cam 22, and the primary winding 23 of an induction coil 24, supplied with a secondary winding 25. Accordingly, while the breaker points are closed, D-C. current flows in the primary winding 23. When the breaker points 21 open, this current is suddenly interrupted, and in accordance with well known laws of electricity a high transient voltage is generated in the secondary winding 25. The secondary winding 25 is connected at one end to the rotary arm 26 of a distributor 27, and at its other end with the principal electrode 8. One of the switch contacts 28 of the rotary distributor 27 is connected to the auxiliary electrode 9. The cam 22 and the switch arm 26 are driven from a synchronous motor 29, which is energized from the line 5. The timing of the cam 22 is so arranged that a break of the breaker points 21 occurs once during each cycle of the voltage supplied by the line 5, and the structural arrangement may be such, in accordance with principles well known in the art, that the precise point in the period of the A-C. voltage supplied by the line 5 at which breaking of the points 21 takes place may be determined by adjusting the phasing of the cam 22.

Accordingly, as the cam 22 rotates the breaker points 21 open and close, and voltage pulses are applied between principal electrode 8 and auxiliary electrode 9, once during each cycle, at times when the anode 2 is positively polarized. When a sufficiently high voltage is impressed from the secondary winding 25 between principal electrode 8 and the auxiliary electrode 9 a discharge occurs, which ionizes the air existing in the gap between the electrodes 7, 8 and 9. When the air is ionized a relatively low resistance path between electrodes 7 and 8 is created, so that essentially ionization of the air is equivalent to closure of a switch across principal electrodes 7 and 8.

The condenser 14, which at this instant is charged in such sense that principal electrode 8 is positive relative to cathode 3, discharges across the gap between electrodes 7 and 8 and from the ignitor electrode 4 to the cathode 3. Discharge of the condenser 14 establishes a sufficiently heavy flow of current from ignitor electrode 4 to cathode 3 to establish an ionized gaseous vapor within the ignitron 1, and the latter then fires, current flowing from anode 2 to cathode 3 and through load 6. Since the breaker points 21 may be constrained to break once during each cycle of the A-C. voltage supplied by the line 5, and at a predetermined point within the cycle, the operation of the system results in successive firings of the ignitron 1, and accordingly of successive pulses of unidirectional current flow in the load 6. The magnitude of this current flow may be readily controlled by controlling the timing of the cam 22.

Referring now more particularly to Figure 2 of the accompanying drawings, there is illustrated a modification of the system of Figure 1, which involves primarily provision of a modified system for developing firing pulses for the ignitor electrode 4. In the system of Figure 2 the voltage supplied by the line 5 is applied directly to

the ignitor electrode 4 instead of via a transformer.

In the system of Figure 2 there are employed breaker points 21, cam 22 for actuating the breaker points alternately into open and closed position, a synchronous motor 29 for driving the cam 22, and a distributor 27, all of which serve to energize the secondary winding 25 of an induction coil 24 periodically in synchronism with the voltage supplied by the line 5. The primary winding 23 of the induction coil 24 is supplied with D-C. current from a rectifier and filter 30, which may comprise, as in the system of Figure 1, a transformer 17, rectifier 18, and filter 19. The voltage generated across the secondary winding 25 is applied between an auxiliary electrode 9 and a principal electrode 8, as in the system of Figure 2. Accordingly each time a high voltage is generated in secondary winding 25 the gas existing in the gap electrodes 8 and 9 becomes ionized. Ionization of the gas reduces the total resistance between the electrodes 8 and 9 to an extremely low value, from an extremely high value, and is equivalent roughly to closure of a switch. A circuit is thereby completed from the positive terminal of the source 30 through the primary winding 31 of transformer 32, from gap 7 to gap 8, through secondary winding 25 of transformer 24, and back to the negative terminal of source 30. There is also thus completed a circuit extending from transformer 24 through primary winding 31 and across the gap between electrodes 7 and 8. The condenser 29 is normally charged to a D-C. voltage, since the condenser 29 is normally charged to the full voltage of the D-C. source 30 while the gap between electrodes 7 and 8 is deionized. Ionization of the gap results then in discharge of the condenser 29 through the primary winding 31 and through the gap, this discharge being of a transient nature, since once the condenser has completed its discharge no further voltage is available for maintaining the spark across the electrodes 7 and 8.

The transformer 32 may be provided with a secondary winding 33, which is connected in series with an R. F. by-pass condenser 34 and a tuning condenser 35. The sudden impact of current flow in the primary winding 31 results in high frequency oscillations, if the value of the condenser 29 and the design of the windings of the transformer 32 are suitable, and the primary circuit comprising primary winding 31 and condenser 29 may be tuned to the same frequency as is the secondary circuit comprising winding 33, tuning condenser 35 and by-pass condenser 34. The high frequency oscillations result in the generation of an extremely high voltage across the secondary winding 33, which, however, are prevented from application to the ignitor electrode 4 by the by-pass condenser 34. Essentially the high frequency voltage is applied then across a spark gap consisting of electrodes 36 and 37 which are connected across the condenser 35. The spark gap comprising electrodes 36 and 37 discharges, thus completing a circuit for current flowing from the line 5 through protective resistance 23, secondary winding 33 of transformer 32, electrodes 36 and 37 ignitor electrode 4, cathode 3, load 6 and to the other side of line 5.

Figure 3 of the accompanying drawings illustrates in cross section a suitable arrangement for the spark gap device comprising electrodes 7, 8 and 9, which is utilized in the system of Figure 2. It will be noted that the electrode 9 is

a sharply pointed electrode co-acting with the electrode 8, which is provided at its face adjacent to the point 40 of electrode 9 with a slightly concave surface 41. The electrodes 8 and 9 further are generally co-axial. Accordingly, upon application of an intense voltage between electrodes 8 and 9, a spark is generated between the point 40 and the surface 41, which effects intense ionization of the air existing in the vicinity thereof. The electrode 7 is in the form of an annulus, having a central aperture symmetrically placed with respect to the axis of the electrodes 8 and 9, and with the plane of the annulus perpendicular to the axis. Additionally, the aperture is arranged to overlap slightly the electrode 8 and is very closely spaced with respect thereto. As a consequence of the intense ionization of the air existing between electrode points 40 and 41, and of the very slight distance which separates electrodes 12 and 13, the passage of current between electrodes 12 and 13 may be very readily effected, even in response to voltages of quite low value, say of the order of 100 volts.

While I have illustrated the present invention as applied to the firing of ignitron tubes, it will be clear that the principles of the invention may find much wider application, and particularly may be employed to effect firing of gaseous conduction electronic devices of various character, including those which utilize mercury cathodes, or are supplied with xenon vapor, or other gaseous media. In addition, the present invention may be extended to the priming of spark gaps operating in free air, as will become evident as the description proceeds, and may be applied not only to rectification of alternating currents, but also to systems for transforming the frequency of alternating currents.

The present invention further finds particular application to the production of a lower frequency current from a higher frequency current, provided by a three phase line, such lower frequency currents having particular application to the art of spot welding or other types of resistance welding with currents of high intensity.

It is well known that the supply of welding machines from a three phase network at commercial power frequencies presents difficulty because of the unfavorable power factor introduced into the network by the character of the welding load, and further because of the dissymmetry of the load introduced into the network.

In accordance with the present invention, it is possible to produce a current of lower frequency from one of higher frequency, by abstracting energy equally from all the phases of a three phase network, while at the same time enabling ready control of the starting time and the welding time of the welding equipment. The necessary control is effected by controlling the distribution of firing sparks, in accordance with a proper sequence, to a plurality of gaseous conduction devices connected between the lines of a three phase line and a welding load.

Reference is now made to Figure 4 of the accompanying drawings wherein is illustrated a system for reducing the frequency of current flowing from a three phase line by means of equipment of the character hereinabove disclosed, or alternatively, for rectification of such current.

The system of Figure 4 utilizes, instead of ignitrons or the like, gaseous conduction devices which are capable of operating in free air, and

which do not require envelopes. When ignitrons are utilized in order to generate alternating currents, as is essential in the process of frequency transformation, it is essential to use a pair of back-to-back tubes, or tubes disposed in inverse parallel relation, in each one of the phases of a three phase line. By utilizing spark gap gaseous conduction devices of the type shown in Figure 4A; operating in free air, on the contrary, it is possible to take advantage of the fact that current may flow in the spark gaps in either direction, thereby reducing the total number of gaseous conduction devices which must be employed.

Referring now more particularly to Figures 4 and 4A of the accompanying drawings, the reference numeral 50 identifies a cam, which actuates a pair of breaker points 51 and 52 in alternation, and each pair alternately into open and closed position. There is further provided a source of D.-C. voltage 53, connected in series with the primary winding 54 of a transformer 55. The breaker points 51 and 52 are connected in shunt with each other, and with the voltage source 53 and the primary winding 54 connected in series. Accordingly, whenever either one of the breaker points 51, 52 is closed a D.-C. circuit is completed for the primary winding 54, and whenever either of the points is suddenly opened, when the other point is also open, an abrupt interruption of current flow in the primary winding 54 will take place. The net effect is, then, the generation in the secondary winding 56 of the transformer 55 of successive high voltage pulses occurring six times for each rotation of the cam 50, these high voltage pulses being equally spaced in time, but being controllable in respect to phase by suitably adjusting the position of the cam 50, or of the breaker points 51, 52 with respect to the cam 50.

One end of the secondary winding 56 is grounded and the other end is connected to the rotary arm 57 of a rotary switch 58 having six equally spaced stationary contacts 59.

The switch arm 57 and the cam 50 are driven in synchronism by means of a synchronous motor 60, so that the high voltage generated in a secondary winding 56 is distributed in succession among the stationary switch contacts 59-64 inclusive, during rotation of the rotary arm 57.

The switch contacts 59 and 62 are connected together and to a first line 66; the switch contacts 61 and 63 are similarly connected together and to another line 67; the succeeding switch contacts 61 and 63 are similarly connected together to a line 67 and the stationary switch contacts 61 and 64 are similarly connected to a further line 68. Since the switch contacts 59, 60, 61, 62, 63, 64 follow each other, in respect to time of contact with arm 57, it follows that the lines 66, 67 and 68 will be successively energized from the secondary winding 56, and that each one of the lines will be twice energized during each cycle of rotation of the cam 50, the rotary switch arm 57, and the drive motor 65.

The voltages applied to the line 66, 67 and 68 are applied respectively to priming voltage generators 69, 70, and 71 which may be specifically of the character of the priming voltage generators disclosed in Figures 1 and 2, and described in detail hereinbefore, and utilized in the embodiments of my invention illustrated in those figures for applying priming current to control electrodes 4 of ignitron 1. Accordingly, at the output of the priming voltage generators 69, 70 and 71 will be

provided pulses of relatively high voltage and current intensity, for application to the gaseous conduction devices 72, 73 and 74 respectively. The latter are provided with priming electrodes 75, 76 and 77, which are broadly equivalent to the ignitor electrodes 4 of the ignitrons 1. While in the case of ignitrons an electrode corresponding with an anode and a further electrode corresponding with a cathode are provided, in the case of the gaseous conduction devices utilized in the system of Figure 4, the anodes and cathodes are interchangeable, since gaseous conduction takes place by means of an arc or spark discharge in air. The principal electrodes of each of the gaseous conduction devices 72, 73 and 74 are in the form of a central cylinder (78, 79, 80) surrounded by a further cylinder (81, 82, 83) with a gap between the cylinders. A magnetic field (not illustrated) may be provided in a direction parallel to the cylinders, to effect rotation of the sparks generated between the principal electrodes. Each one of the outer cylinders 81, 82, 83 is connected via a suitable choke 84, 85, 86, respectively to ground. The inner cylinders 78, 79 and 80 respectively, are connected to the separate phases 87, 88, 89, of a three phase power source 90, connected in Y, and with its neutral point connected to one end of a load 91, the other end of which is grounded.

If we assume now that priming sparks are applied to the priming electrodes 75, 76 and 77 of gaseous conduction devices 72, 73 and 74, respectively, approximately at the initiation of a cycle of voltage in the corresponding phases 87, 88 and 89 of the three phase source 90, and while the voltages are positive going, the gaseous conduction devices 72, 73, 74 will pass positive current through the load 91 and back to the neutral point of the three phase source 90 in pulses of half wave sine shape, mutually displaced by 120°, as shown at lines 108, 101 and 102 of Figure 6. On the other hand, if the priming takes place while the voltages are negative going the current flow in the load will be in the opposite direction, and similarly displaced by 120°, as illustrated at lines 103, 104, 105 of Figure 6. If, as in the system of Figure 4 the priming takes place on both negative and positively going voltages, in the separate phases of the three phase line, current flowing in the load 91 will be of alternating character, or will reverse in frequency. If, furthermore, the rate of rotation of the arm 57 of the rotary switch and the rate of rotation of the cam 50 is not in synchronism with the alternating voltages supplied by the three phase line 90, there will be generated in the load 91 a current the frequency of which is dependent upon the speed of rotation of the cam 50 and of the arm 57, and in general a lesser frequency will be so generated, various wave forms or frequencies being possible by suitable selection of the rates of rotation. At the same time the magnitudes of the current flowing may be controlled by adjusting the phasing of the priming voltages supplied to priming electrodes 75, 76, 77, respectively, by adjusting the phasing of the rotary switch arm 57 and the cam 50. By disconnecting certain of the switch contacts such as 62, 63, 64 or 59, 60, 61 the system may be utilized for rectification, and the rectified current may be caused to flow in either direction, depending upon which set of three contacts is eliminated from the circuit.

A set of gears with definite ratios (not shown) may be interposed between the cam 50 and the commutator, so that the wave form may be

changed as required by permutation of the timing of circuit breaking with respect to the contacts established by the commutator arm. Another way of achieving a similar result is by disconnecting the contacts from their leads in permutations such that the proper alternance of phase be discontinued in a predetermined fashion.

The system of Figure 4 may be duplicated utilizing ignitrons in place of the gaseous conduction devices 72, 73, 74, which operate in air, and which are inherently bi-directional. In such case, however, each phase of the line must be supplied with two back-to-back or inversely parallel connected ignitrons, as illustrated in Figure 5 of the accompanying drawings. The mode of controlling the times of energization of the ignitrons, however, may be entirely analogous with that illustrated in Figure 4 of the drawings.

There is further illustrated in Figure 5 of the drawings, a mode of connection of a plurality of ignitrons with a welding transformer 110 having a secondary winding 111 and welding electrodes 112. This may be accomplished by connecting ignitron pairs 113, 114, 115, 116, 117, 118 in inverse parallel relation between each pair of lines of the three phase source 120, and by connecting each pair of ignitrons in series with a separate priming winding, as 121, 122, 123, all of which are wound on the same core 124, and all of which are so wound as to provide additive currents in the secondary winding 111. By controlling the cadence in which the ignitrons are fired, as in the system of Figure 4 of the drawings, various wave forms may be caused to appear in the secondary winding 111, and the frequency of the current flowing in the winding 111 may be reduced with respect to the frequency present on the three phase line 120, in various ratios.

Referring particularly to Figure 7 of the drawings there is illustrated at line A, a graph of the alternating voltage present in one phase of the three phase network. By sequentially transferring current through the ignitrons in succession in groups of two time adjacent phases of the three phase line, it is possible to obtain a frequency in the welding load which is equal to three-fifths of the fundamental frequency of the three phase line, as at curve B.

By energizing the ignitrons in alternation in groups of three successive phases, it is possible to obtain a wave form in accordance with curve C, which corresponds with a frequency equal to three-sevenths of the fundamental frequency of the three phase line.

By energizing in alternation in groups of four successive phases of the three phase line, it is possible to obtain a wave form corresponding with that illustrated at D of Figure 7, which corresponds to a frequency equal to three-ninths, or one-third, of the fundamental frequency.

By energizing in alternation in groups of five successive phases, it is possible to obtain a wave form corresponding with E of Figure 7, which corresponds to three-elevenths of the fundamental frequency.

Other possibilities will occur to those skilled in the art.

Reference is now made to Figure 8 of the accompanying drawings, which provides a basis for further explanation of the mode of energization of the ignitrons in order to provide the wave form illustrated at line B of Figure 7, the wave form being provided in Figure 8, at line B, corresponding with that shown in Figure 7, line B. The pulses illustrated at lines 130, 131 and 132 have

11

been numbered with the numerals corresponding with the ignitrons of Figure 5, so that considering Figure 8 as a timing diagram for firing the ignitrons of Figure 5 by successive pulses, and reading from left to right, pulses must be applied to the ignitrons as numbered, to provide the output wave form shown at line B. It will be seen that the cycle of events involves twelve operations, after which the cycle repeats itself.

A similar diagram is shown in Figure 9 for generating the wave form shown at line C thereof, the timing pulses being shown related in time to the wave form diagram. The groups of ignitrons of Figure 5 may be designated as A, B and C, in the separate phases, and each of the ignitrons may be given a plus or minus designation, in accordance with the direction in which it passes current. Provided with this key, it will be evident that the pulses shown at line 140 represent those applied to ignitrons 113 and 114, those shown at line 141 represent the pulses applied to ignitrons 115, 116, and those shown at line 142 correspond with the pulses applied to the ignitrons 117, 118. To determine to which of a pair of ignitrons the pulse is applied it is merely necessary to perceive whether a plus or minus indication is adjacent the pulse. The overall pulse generating requirement is indicated at line 23 of the diagram.

While I have not shown any specific distributing arrangement for distributing the pulses shown at line E of Figure 7, at line 133 of Figure 8, at line 143 of Figure 9, such arrangements will be obvious to those skilled in the art, and the necessary techniques are those utilized commonly in distributing ignitron pulses to gasoline engine cylinders, at the present time.

While I have described and illustrated various specific embodiments of my invention, it will be clear that variations in detail and in general arrangement may be resorted to without departing from the true spirit and scope of the invention as defined in the appended claims.

What I claim and desire to secure by Letters Patent of the United States:

1. In combination, in a system for controlled firing of gaseous conduction electronic devices, a gaseous conduction electronic device having an anode, a cathode, and a control electrode, a spark generating device comprising three mutually adjacent electrodes in a gaseous atmosphere, means for establishing ionization in said gaseous atmosphere between two of said mutually adjacent electrodes, said last means comprising a source of relatively high transient voltage and relatively low current, means responsive to said ionization for establishing ionization current flow between one of said last mentioned two electrodes and the third of said three mutually adjacent electrodes, said last means comprising a source of relatively low voltage and relatively high current, and a circuit comprising said last mentioned two electrodes and said control electrode in series.

2. The combination in accordance with claim 1 wherein said gaseous conduction electronic device is a device having a liquid metallic cathode and wherein said control electrode is an ignitor electrode.

3. The combination in accordance with claim 1 wherein said gaseous conduction electronic device is an ignitron.

4. The combination in accordance with claim 1 wherein said gaseous conduction electronic device is a thyratron.

12

5. The combination in accordance with claim 1 wherein said gaseous conduction electronic device is a spark gap device.

6. The combination in accordance with claim 1 wherein said gaseous atmosphere is air.

7. In combination, in a system for controlled firing of gaseous conduction electronic devices, a plurality of gaseous conduction electronic devices, each of said plurality of gaseous conduction electronic devices having an anode, a cathode and a control electrode, a source of firing voltage for said devices, a source of direct current, a circuit maker and breaker, an induction coil having a primary and a secondary winding, a circuit interconnecting said source of direct current, said circuit maker and breaker and said primary winding, means actuating said circuit maker and breaker periodically to initiate and terminate current flow in said primary winding, thereby to induce high voltage pulses in said secondary winding, a separate sparking device associated with each of said devices and comprising three spark electrodes mutually adjacent and separated by relatively small gaps, a gaseous atmosphere in said gaps, means for connecting said secondary winding across two of said spark electrodes of one of said sparking devices, a source of relatively high current and low voltage, means for connecting said last mentioned source across one of said two spark electrodes and the remaining one of said three spark electrodes of said one of said sparking devices, and a circuit connecting in series said last mentioned source and said one of said two spark electrodes and said remaining one of said three spark electrodes of said one of said sparking devices, and means connecting said secondary winding with said separate sparking devices periodically in a predetermined order.

8. The combination in accordance with claim 7 wherein said gaseous conduction electronic devices are devices having liquid metallic cathodes, and wherein said control electrodes are ignitor electrodes.

9. The combination in accordance with claim 7 wherein said gaseous conduction electrode is an ignitron.

10. The combination in accordance with claim 7 wherein said gaseous conduction electronic device is a spark gap device.

11. The combination in accordance with claim 7 wherein said gaseous conduction electronic device operates in air.

12. The combination in accordance with claim 7 wherein said gaseous atmosphere is air.

13. The combination in accordance with claim 7 wherein said source of relatively high current and low voltage comprising a charged condenser.

14. The combination in accordance with claim 7 wherein said source of relatively high current and low voltage comprises a source of alternating voltage of a predetermined frequency, and wherein a voltage of said predetermined frequency is applied between anode and cathode of each of said gaseous conduction electronic devices.

15. The combination in accordance with claim 1 wherein is further provided a source of alternating voltage, and means connecting said alternating voltage between said anode and said cathode, and wherein said source of relatively high transient voltage comprises a circuit having in series therewith a circuit maker and breaker, and wherein said circuit maker and breaker is operated in synchronism with said alternating current, and wherein said source of relatively low

13

voltage and relatively high current further comprises said source of alternating voltage.

16. In combination with a source of polyphase A.-C. voltage, at least one gaseous conduction device connected in circuit with each phase of said source of polyphase voltage, each of said gaseous conduction devices comprising an anode, a cathode and a control electrode, means for firing said gaseous conduction devices in a predetermined sequence and each during a period of said A.-C. voltage, said means for firing each of said gaseous conduction devices comprising a separate main spark gap in air and having an auxiliary starting electrode, means for generating a high voltage on said auxiliary starting electrodes in sequence and transiently in response to each cycle of said A.-C. voltage to ionize said air, and means responsive to ionization of said air to transfer priming current across said main spark gap, said last means comprising said source of A.-C. voltage, and means for transferring said priming current between said cathode and said control electrode.

17. The combination in accordance with claim 16 wherein said gaseous conduction devices each 25 comprises a liquid cathode and wherein said control electrodes are igniter electrodes.

14

18. The combination in accordance with claim 16 wherein said gaseous conduction devices are sparking devices operative in air.

19. The combination in accordance with claim 5 16 wherein said at least one gaseous conduction device connected in circuit with each phase of said source of polyphase voltage comprises a pair of back-to-back connected gaseous conduction devices connected in circuit with each of said phases.
